(57) **CLAIM**

The ornamental design for a secondary electrical distribution spool insulator, as shown and described.

DESCRIPTION

FIG. 1 is the top plan view of a spool insulator showing my new design;

FIG. 2 is a bottom plan view thereof;

FIG. 3 is a side elevation view thereof;

FIG. 4 is a top plan view of a modified embodiment of the spool insulator;

FIG. 5 is a bottom plan view of FIG. 4;

FIG. 6 is a side elevation view of FIG. 4;

FIG. 7 is a top plan view of a second modified embodiment of the spool insulator;

FIG. 8 is a bottom plan view of FIG. 7; and,

FIG. 9 is a side elevation view of FIG. 7.

The broken line portions of the spool insulator are for illustrative purposes only and form no part of the claimed design.
